UNITED STATES PATENT OFFICE.

GEORGE HOLMES, OF BOGALUSA, LOUISIANA.

BUCKET.

Application filed September 19, 1925. Serial No. 57,420.

This invention relates to receptacles adapted to hold water for filling radiators of automobiles or the like, and has for an object the provision of a receptacle preferably having a flexible body such as canvas in order that the receptacle may be folded to occupy comparatively little space in an automobile, the said body being associated with novel means for retaining water therein and means operative to actuate the retaining means to unseat it when the receptacle is in position to discharge water into a filling tube of a radiator.

A further object of this invention is to produce means whereby the weight of the container and parts associated with it and the weight of the contents thereof will serve to unseat the guard that retains the water in the receptacle, thus increasing the convenience of the application of the device to a radiator filling tube and the discharge of the contents of the receptacle into a radiator.

It is a still further object of this invention to produce novel means whereby the fluid retaining device may be returned to normal or closed position after the contents of the container has been discharged.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a view in elevation of a fragment of a radiator showing a device embodying the invention applied thereto;

Figure 2 illustrates an enlarged sectional view of the discharge spout of the container or holder in normal position prior to the opening of the guard or valve; and

Figure 3 illustrates an enlarged sectional view showing the connection between the handle and the bucket.

In these drawings, 5 denotes a receptacle or bucket-like structure preferably made of canvas and provided at its mouth with a sectional brace or spreader 6 which serves to hold the mouth distended and to prevent its collapse when the bucket and its contents are supported by the handle 7. The brace is preferably formed of flat metal having a pivot 8 whereby the sections are oscillatably

connected and each section has an aperture 9 at its outer end to receive a link or ring 10 that may be secured to the bucket in any appropriate way. One member of the brace has a projection 11 which engages the under surface of the coacting section to limit the swinging movement of the sections with relation to each other in one direction, but the arrangement of parts is such that the joint between the sections may break to permit the sections to lie parallel or approximately so, when extending downwardly into the bucket or receptacle.

A funnel-like nozzle 12 is adapted to be inserted in the filling tube or spout 13 of an automobile radiator 14, and the said funnel has an annular flange 15 that embraces the lower end of the wall of the bucket or receptacle. The material of the receptacle or bucket is held between the flange 15 and the flange 16 of an apertured plate 17 by fastenings 18 such as bolts, rivets or the like. The plate 17 has a central aperture 19 and it may have a depending annular flange 20, through which the contents of the bucket or receptacle is discharged. Preferably the plate is shaped to form a seat 21 having a gasket or packing 22 to effect a fluid-tight joint between the valve 23 and its seat, which valve guards the opening in the plate and prevents discharge of liquid from the bucket or receptacle until the said valve is unseated, as will presently appear.

In the present embodiment of the invention, a cylindrical sleeve 24 of foraminous metal or wire mesh is arranged to slide vertically through the aperture of the plate 17 following the valve upwardly as it is unseated and the said foraminous cylindrical sleeve acts as a strainer to prevent dirt or foreign substances in the water from gaining access to the interior of the cooling system of an automobile, it being shown that the sleeve will rise with the valve and guard the opening through the plate for the purpose indicated.

As a means for holding the valve seated and for displacing the valve from its seat when desired, the valve is supplied, in the present embodiment of the invention, with two depending rods 27 having their ends anchored to the valve in any appropriate way, which need not be described in detail, and the said rods each has an angularly disposed portion 25 and 26 extending through a slot 28 in the funnel in order that the said

angularly disposed portions may be applied to the top of a radiator filling tube with the discharge end of a nozzle in the tube for delivering water to the radiator.

5 The rods are held in positions to yieldingly retain the valve on its seat by a spring 29 which has its upper end bearing against the under surface of the plate 17 and its lower end bearing against the angularly disposed portions or arms 25 and 26 of the rods 27, and hence, said rods are held normally projected toward the end of the nozzle and they may move longitudinally of the nozzle when the weight of the bucket and its 15 contents overcomes the resistance of the spring which serves to hold the valve on its seat.

It will be apparent from an inspection of the drawing and from the foregoing description that if the bucket or receptacle contains water and the nozzle thereof is applied to a radiator filling tube the angularly disposed ends of the rods will be supported on the filling tube and the nozzle 25 will descend into the filling tube, a movement which will cause the unseating of the valve and a movement of the strainer vertically. When the parts are in the position just indicated, water will flow from the bucket or receptacle through the strainer and through the nozzle to the radiator, whereas the valve will again seat itself when the bucket is removed from the radiator tube. Should any deposits of foreign substance occur which would prevent the valve 35 from seating, it can be removed prior to the filling of the bucket.

I claim:

1. In a bucket, a body normally open at 40 its lower end, a bottom plate having an aperture in its approximate center and having a flange fitting against the inner wall of the body at its lower end, a valve seat formed in the plate around the aperture, a 45 conical element extending below the bottom of the body and having an upstanding flange embracing a part of the outer sur-

face of the body at its lower end, means for fastening the flanges of the plate and the conical element to the body, a valve for controlling the opening in the plate, and means connected thereto and extending externally of the conical element for moving the said valve from its seat. 50

2. In a bucket, a body normally open at its lower end, a bottom plate having an aperture in its approximate center and having a flange fitting against the inner wall of the body at its lower end, a valve seat formed in the plate around the aperture, a 60 conical element extending below the bottom of the body and having an upstanding flange embracing a part of the outer surface of the body at its lower end, means for fastening the flanges of the plate and the 65 conical element to the body, a valve for controlling the opening in the plate, means connected thereto, and extending externally of the conical element for moving the said valve from its seat, and means for normally 70 maintaining the valve on its seat.

3. In a bucket, a body normally open at its lower end, a bottom plate having an aperture in its approximate center and having a flange fitting against the inner wall of 75 the body at its lower end, a valve seat formed in the plate around the aperture, a conical element extending below the bottom of the body and having an upstanding flange embracing a part of the outer surface 80 of the body at its lower end, means for fastening the flanges of the plate and the conical element to the body, a valve for controlling the opening in the plate, means connected thereto, and extending externally of 85 the conical element for moving the said valve from its seat, means for normally maintaining the valve on its seat, and a strainer within the conical element and movable upwardly through the aperture of the plate with the upward movement of the valve displacing means. 90

GEORGE HOLMES.
